CARBURETOR ACCELERATING PUMP

Joseph Schweiss, St. Louis, Mo., assignor to
 Carter Carburetor Corporation, St. Louis, Mo.,
 a corporation of Delaware

Application January 16, 1939, Serial No. 251,214

3 Claims. (CL 103—148)

This invention relates to fluid pump devices and consists particularly in novel construction of the pressure chamber and valve portions thereof.

5 The invention is shown applied to the accelerating pump of an internal combustion engine carburetor although it may be readily adaptable to a variety of different uses.

An object of the invention is to eliminate the 10 leakage and wear which accompanies the use of fluid pumps utilizing reciprocating pistons. Another object is to provide greatly simplified inlet and outlet valve structure for a fluid pump.

These objects and other more detailed objects 15 hereafter appearing are attained substantially by the structure illustrated in the accompanying drawings in which

Fig. 1 is a vertical transverse section of an internal combustion engine carburetor.

20 Fig. 2 is a partial vertical section of the carburetor and taken on a different plane than Fig. 1.

Fig. 3 is an enlarged view showing a part of the structure in Fig. 2.

25 Fig. 4 is a horizontal section taken on the corresponding section line of Fig. 3, and

Fig. 5 is a view similar to Fig. 3 but showing a modification.

The carburetor in Figs. 1 and 2 has a down-draft mixture conduit including air inlet horn 1, 30 venturi 2, and outlet portion 3, flanged as at 4 for attachment to the intake manifold of an associated internal combustion engine (not shown).

A choke valve 5 is pivotally mounted in the air 35 horn on shaft 6 which extends, at one end, into a housing 7 enclosing automatic choke controlling mechanism. A throttle valve 8, near the lower end of the mixture conduit, is provided with a crank 9 for manual control. Adjacent the 40 mixture conduit is a bowl 10 within which fuel is maintained at a substantially constant level by means of the usual needle valve mechanism 11, controlled by float 12. Fuel is supplied to the bowl by means of an inlet connection 13 and, during normal operation, is supplied to the 45 mixture conduit through a calibrated metering orifice member 14, controlled by stepped metering rod 15, and main nozzle 16 discharging into the throat of the smallest venturi 2.

50 An arm 17 is mounted on the throttle shaft opposite crank 9 and is connected by means of a link 18 to a rock lever 19 centrally fulcrumed upon a pillar block 20 projecting upwardly from the float bowl cover 21. As shown in Fig. 1, metering rod 15 is carried by lever 19 between

its connection to link 18 and the fulcrum. At the opposite end of lever 19, as shown in Fig. 2, a piston rod 22 is connected to lever 19 by means of a small link 23.

Piston rod 22 extends through bowl cover 21 5 and, at its lower end, is rigidly connected to the upper wall of a pliable sack, generally indicated at 24, received within tubular guide 25 extending between top and bottom portions of the float bowl. An inlet passage 26 connects the float 10 bowl with the interior of sack 24 and an outlet passage 27 connects the sack with a small nozzle 28 discharging into the mixture conduit adjacent venturi 2.

Sack 24, as better shown in Figs. 3 and 4, includes cylindrical side wall structure 29 and end walls 30 and 31. Side wall structure 29 and end wall 30 are preferably formed of a continuous sheet of a suitable gasoline resistant, pliable material such as synthetic rubber. Piston rod 22 15 is secured to end wall 30 for the application of pumping pressures to the sack. A series of longitudinally spaced circumferential ribs 32 extend between the outer surface of side wall structure 29 and engage the inner surface of tubular guide 25 so as to provide spaces, as at 33, between the 20 guide and the portions of wall structure 29 between ribs 32 to accommodate bulging or flexing of the side wall structure during the application of pumping pressures thereto. Guide 25 functions to restrict distortion of sack 24 to the 25 bulging and collapsing movement normally incident to pumping.

The other end wall 31 has an opening 34 communicating with inlet passage 26 and a second 35 opening 35 communicating with outlet passage 27. Wall 31 may be formed of a block of molded material, such as synthetic rubber, with projecting nipples, as at 36 and 37, projecting oppositely therefrom and normally closing orifices 34 40 and 35. These nipples are of resilient material and have central apertures which are normally closed but which yield when fluid pressures are applied thereto in one direction only to permit the passage of fluid therethrough. Nipple 36 is 45 arranged to function as an inlet valve to permit drawing of fluid through orifice 34 into sack 24 when the latter is expanded due to upward movement of piston rod 22. Nipple 37 functions as an outlet valve for admitting fuel to outlet passage 27 when the sack is collapsed. During the discharge, nipple 36 remains tightly sealed and during charging of the sack outlet nipple 37 remains tightly sealed.

The side wall structure of sack 24 in Figs. 1-4 55

is preferably formed of resilient material so as to return to its original shape of its own accord. In Fig. 5 there is shown a coiled spring 38 in the interior of sack 24 for urging upper end wall 36 in an upwardly direction. The other elements of the structure in Fig. 5 are the same as in the previous form.

The arrangement, form, and adaption of the pump device may be modified in various ways.

- 10 5 For instance, lower end wall 31 may be formed of any suitable material and inlet and outlet valve nippies 36 and 37 may be separately formed and secured thereto. I have shown tubular guide 25 resting on the upper edge of a shoulder 39 formed on the lower extremity of sack 24 for holding this extremity in fluid tight engagement with the bottom wall of the bowl, guide 25 being held down by bowl cover 21. This arrangement of parts is not essential and also the form of the 15 0 tubular guide 25 may be carried substantially without detracting from its function as guiding and bracing means for the pliable sack. The exclusive use of all modifications as come within the scope of the appended claims is contemplated.

5 I claim:

1. A fluid pump device comprising a sack having wall structure at least partly of yielding material, inlet and outlet valves in said wall structure, means for applying alternate expanding and collapsing pressures to said structure for drawing fluid thereinto and expelling the same therefrom, 30

said sack comprising side wall structure of pliable material and end walls, there being circumferential ribs on said side wall structure, and guide means extending along said side wall structure and engaging said ribs, the portions of said side wall structure between said ribs being spaced from said guide means whereby said portions may bulge and contract during application of pumping pressures to said sack. 5

2. A fluid pump device comprising a sack 10 formed substantially of pliable material having side and end walls, circumferential ribs on the outer surface of said side wall, guide means extending along said wall and engaging said ribs for limiting distortion of said sack to the bulging and contracting incident to pumping, inlet and outlet valves in one of said end walls, and means for applying pumping pressures to the opposite end wall. 15

3. A fluid pump device comprising a rigid tubular guide, a sack formed substantially of pliable material inside said guide, said sack having wall structure including side and end walls, circumferential ribs spaced longitudinally along said side walls and engaging said guide, inlet and outlet valves in said wall structure, and means for alternately applying pushing and pulling forces to one of said end walls to produce bulging and contraction of the portions of said side walls between said ribs. 20 25
